FILLING MACHINE

Robert J. Stewart and Frank S. Bell, Baltimore,
Md., assignors to Crown Cork & Seal Company,
Inc., Baltimore, Md., a corporation of New York

Application May 26, 1948, Serial No. 29,235

13 Claims. (Cl. 226—117)

1

The present invention relates to filling machines.

Heretofore, the raising and lowering movements of the container supporting platforms of filling machines have been controlled by engagement of rollers carried by the platform structure with guideways and a cam. If a roller or the bushing associated therewith became worn, either the roller or bushing, or both, had to be entirely replaced.

An object of the invention is to provide improved arrangements for controlling the raising and lowering movements of the container supporting platforms of a filling machine.

The present invention includes the provision upon container supporting platforms of elements provided with planar surfaces to engage opposed faces of either the guideways or a cam, or both. The use of blocks with planar surfaces arranged at the proper angles enables the moving parts to be controlled without the provision of bearings such as have been necessary where rollers are used to control the raising and lowering movements. The invention also includes the provision of blocks of such design that they can be adjusted to provide new surfaces for use after previously used surfaces become worn.

Another object of the invention is to provide an improved arrangement for lubricating the vertically movable parts of container supporting platforms.

It has been usual to journal the filling table and other rotary tables of a filling machine upon base pedestals by the use of ball or roller bearings. Such bearings are relatively expensive, because they must support a substantial weight as well as a downward thrust acting upon one peripheral portion of the table.

An object of the invention is to provide an improved means for journaling the rotary tables of filling machines.

The present invention involves the provision as a table journal of opposed annular metal rings positioned between the table and the pedestal and which rings are of such design that their bearing surfaces may be adequately lubricated. The invention also contemplates resilient support for the rings to compensate or take up any tilting thrust, such as the downward thrust effective upon one peripheral portion of the filling table or the crowning table of the filling machine. In a more detailed aspect, the invention involves provision of a resilient and confined gasket as a thrust take-up medium.

As is disclosed in Patent No. 2,145,765, for Filling Machine, issued January 31, 1939, on the ap-

2

plication of George J. Huntley and Robert J. Stewart, beverage filling machines are usually provided with means whereby the counterpressure trip will be rendered ineffective to operate the filling valve in the event that a container supporting platform does not have a container delivered thereto.

As is disclosed in Patent No. 2,353,523, for Filling Machine, issued July 11, 1944, on the application of Robert J. Stewart and Harry J. Rever, one manner of operating a counterpressure trip to non-valve actuating position is by the use of an electromagnet which, when energized, will withdraw the trip from the path of movement of the valve arm. Under some circumstances, the counterpressure trip may become momentarily seized against movement to non-actuating position. In order to prevent such seizure from damaging the electromagnet or solenoid, it has been usual to provide electrical overload protection.

A further object of the present invention is to provide a means effective to prevent seizure of a counterpressure or similar trip from damaging its actuating solenoid.

The above object is attained in the present invention by providing a resilient take-up between the trip and the solenoid, the connection between the two also preferably being of swivel type so that the trip will be less apt to become seized.

As is disclosed in Patent No. 2,367,899, for Method and Apparatus for Filling Carbonated Beverages, issued January 23, 1945, on an application filed by Robert J. Stewart, it has heretofore been proposed to provide a snift valve of poppet type in the filling head of a beverage filling machine.

An object of the present invention is to provide a poppet valve snift for a filling machine which is of extremely simple construction and of such design that the snifted gas will be directed inwardly of the filling table.

Other objects and advantages of the invention will be apparent from the following specification and accompanying drawings, in which drawings,

Figure 1 is a vertical axial section through the filling table and filling table pedestal of a filling machine, the view including a vertical axial section of a container supporting platform.

Figure 2 is a developed view taken on a line corresponding to the line 2—2 of Figure 1. The container platforms of Figure 2 differ from those of Figure 1 in that they are adapted to be moved upwardly by fluid pressure.

Figure 3 is an enlarged view of the portion of Figure 1 indicated by the arrow designated 3, but

with additional parts in axial section. Figure 3 is also a section on the line 3—3 of Figure 2 but omitting the fluid supply means of the latter figure.

Figure 4 is a view looking toward Figure 3 from the right.

Figure 5 is a detail sectional view on the line 5—5 of Figure 4.

Figure 6 is a horizontal sectional view taken on the line 6—6 of Figure 4.

Figure 7 is an enlarged detail view showing the container supporting platform lubricating arrangement which is also shown on a smaller scale in the upper left-hand portion of Figure 1.

Figure 8 is a horizontal section on the line 8—8 of Figure 7.

Figure 9 is an axial section showing the table journaling means of the present invention. Figure 9 shows the bearing ring of Figure 11 in diametrical section on the line 9a of Figure 11, the bearing ring of Figure 13 in diametrical section on the line 9b of Figure 13, and the bearing holder of Figure 15 on the diametrical line 9c.

Figure 10 is another section of the table journaling means, and taken on the angled line 10c—10c of the Figure 15 bearing holder.

Figure 11 is a plan view showing the bearing face of one of the bearing rings of the invention.

Figure 12 is a sectional view taken on the angled line 12—12 of Figure 11.

Figure 13 is a plan view of the bearing face of another bearing ring.

Figure 14 is a sectional view taken on the angled line 14—14 of Figure 13.

Figure 15 is a plan view of the bearing holder.

Figure 16 is a sectional view on the angled line 16—16 of Figure 15.

Figure 17 is a sectional view on the angled line 17—17 of Figure 15.

Figure 18 is a vertical sectional view through a counterpressure trip mechanism and control means therefor, the view also including an elevation of a container supporting platform.

Figure 19 is a detail showing the counterpressure trip in axial section.

Figure 20 is a view showing the counterpressure and filling trips of Figure 18 in plan.

Figure 21 is an axial section through a filling head with the snift valve in closed position. The valve body of Figure 21 is shown in section on the line 21—21 of Figure 23. The snift passage outlet, being out of section, is shown in dotted lines.

Figure 22 shows the snift valve of Figure 21 in open position, and

Figure 23 is a rear view of the filling valve body and, more particularly, a view taken on the line 23—23 of Figure 21.

Referring to Figure 1, the numeral 30 designates the filling machine base, which includes a pedestal 32 for the filling table 34. A stationary table 36 is also secured to the base 30 in the usual manner. It will be observed that the general arrangement of these elements is similar to that disclosed in the above-mentioned Huntley and Stewart Patent No. 2,145,765 and, as is the case in the machine of that patent, the base 30 of the present machine would also include suitable pedestals, not shown, for the crowning mechanism and any syruping mechanism.

The liquid to be flowed into the bottles, for example, a soft drink or beer, will be delivered to the machine through a supply line 38 including a pipe 40 which extends upwardly to the filling reservoir, not shown, through a tubular

post 42 fixed in the pedestal 32. The filling table 34 includes a depending central skirt 44, and the bearing structure of the present invention, generally designated by the numeral 46, serves to rotatably support the filling table upon the pedestal 32. At its periphery, the filling table 34 is provided with bores or sockets formed by depending sleeves 48 and filling platforms 50 are vertically reciprocable in these sockets. The filling platforms illustrated in Figures 1 and 3 are adapted to be moved to the upward or filling position indicated at the ends of Figure 2 by the action of springs designated 52 in Figure 1 and as is referred to in the above-mentioned Huntley and Stewart patent. The filling platforms illustrated in Figure 2 are designed to be moved upwardly by fluid pressure in the manner referred to in Patent No. 2,202,033, for Filling Machine, issued May 28, 1940 on the application of Robert J. Stewart and Wiltie I. Gladfelter. Therefore, the filling platforms 50 of Figure 2 have a fluid pressure supply pipe 54 connected thereto to supply the fluid medium.

Referring now to the means of the present invention for controlling the vertical movement of container supporting platforms 50 of both types, this mechanism is disclosed in Figures 1 to 6. As is best shown in Figures 1, 3 and 4, each container supporting platform 50 includes a relatively long tube 56 to the upper end of which the container supporting block or platform is secured.

The cylinder 56 is reciprocable in a sleeve 60 secured in the bore of the sleeve 48 which is integral with the filling table. As best shown in Figure 6, at its lower end, each tube 56 has a member 62 secured thereon. Each member 62 includes a collar portion 64 threaded upon the tube 56, and also includes a radially projecting pin portion 66. Pin portion 66 serves as a carrier for a cam engaging block 68 and a guideway engaging block 70. As shown in Figures 3 and 6, the pin portion 66 is of uniform diameter and fits into central apertures in the blocks 68 and 70. A plate or washer 72 and a machine screw 74 serve to hold the blocks in contact with each other and against a shoulder 76 at the inner end of the pin portion, the washer seating in a recess in the outermost and cam engaging block 68. The inner and unthreaded end of the machine screw 74 extends into an aperture 78 in tube 56 to serve as a dowel pin. In order to further prevent member 62 from turning about cylinder 56, two other dowel pins 79 may be provided as shown in Figure 6. The two blocks 68 and 70 are secured against relative turning movement by dowel pins 80 as indicated in Figures 4 and 5. As is hereinafter explained, the guideway engaging block 70 of each container supporting platform will always be in engagement with bearing surfaces of vertical guide rods 82 depending from the filling table and secured together at their lower ends by ring elements 84. Thus, the guideway engaging blocks 70 will be held against any turning movement upon pin portion 66 and because the cam-engaging blocks 68 are secured to the blocks 70, the blocks 68 also will be held against turning movement.

Referring to Figures 2 and 4, it will be observed that the guideway engaging blocks 70 are of square outline and that two opposite faces thereof engage the bearing surfaces of the guides 82. As a result, the blocks 70 guide the vertical raising and lowering movements of the container supporting platforms 50. This motion of the platforms is further guided by the inner sleeves

86 secured in the ring 84. If the surfaces of a block engaged with the guides 82 become worn so that play occurs, the block 70 can readily be removed and rotated 90° to position the other two surfaces of the block in guiding relationship with the guides 82. The provision of square blocks for this purpose is advantageous over the previous use of rollers because the position of the blocks can be changed as described above when wear occurs. Because of the large bearing surfaces provided by the faces of a block 70, an efficient and true guiding action is obtained.

As is best shown in Figures 2 and 4, the cam-engaging blocks 68 may be described generally as square in outline but have their corners and certain surfaces thereof so inclined or bevelled as to best co-act with the complementary surfaces of the cam 90 which controls the lowering and raising of the container supporting platforms 50. As is shown in Figures 1 and 2, the cam 90 is positioned on the base of the machine inwardly of the circular path of movement of the container supporting platform cylinders 56 with filling table 34.

In accordance with usual practice, successive container supporting platforms and their cylinders 56 will move from the left-hand end of Figure 2 and the downward incline 92 of cam 90, each platform then bearing a bottle or other container which has been filled. The left-hand end 92 of the cam 90 will engage a surface 92a (Figure 4) on block 68 and which surface is on the leading side of the upper face 94 of the block 68. It will also be noted that surface 92a is adjacent the midway point of the surface 94. For example, surface 92a may be inclined downwardly from the horizontal by an angle of about 12°. The surface 92 of cam 90 is inclined at a complementary angle. The surface 92 of cam 90 will thereby initiate the lowering movement of a container supporting platform 50.

Continued rotation of the filling table 34 will bring the cam-engaging block 68 of a platform adjacent the more steeply downwardly inclined surface 96 of cam 90 so that the more steeply inclined surface 96a (Figure 4) of cam block 68 will engage surface 96. Surface 96a would be inclined downwardly from the horizontal by an angle of approximately 30° and cam surface 96 would be inclined at a complementary angle. The container supporting platform will be further and more rapidly drawn downwardly while surface 96a of the block is in contact with surface 96 of cam 90.

When the filling table has rotated sufficiently to the right with respect to Figure 2, the upper central and horizontal surface 94 of a cam block 68 will move beneath the surface 98 of cam 90, surface 98 being a dwell and horizontal. While the block is in contact with this surface, the container supporting platform 50 will be held downwardly as indicated at the central portion of Figure 2 so that the filled bottle or container may be removed and an empty bottle placed on the platform in accordance with the usual practice. Then the cam block 68 will move upwardly along the rise 100 of cam 90, the rise being arranged, for example, at an angle of about 40° from the horizontal. The inclined surface 100a at the trailing end of the upper face of cam block 68 will engage cam surface 100, surface 100a being inclined at a complementary angle. The container supporting platform will rise as the surfaces 100 and 100a are in contact and before the block moves entirely out of engagement with the

cam, the outgoing surface 102 of cam 90 will be engaged by the block surface 102a provided between horizontal surface 94 and inclined surface 100a. Surface 102a is inclined downwardly from the horizontal by an angle of approximately 5° and surface 102 of the cam is arranged at a complementary angle.

It will be understood that the angles discussed above may be varied to meet varying conditions; for example, the rapidity with which a container supporting platform is to be lowered and raised.

It will be observed from the above that the face of cam block 68 which is shown uppermost in Figures 2 and 4 thus includes five surfaces arranged at different angles, each of which is at such angle with respect to the horizontal as to respectively cooperate with the five complementary surfaces of the cam 90. As is illustrated in Figure 4, the face of block 68 shown lowermost is provided with surfaces 96b, 92b, 94b, 102b and 100b identical in inclination with the surfaces of the upper face. It will also be noted that by removing the machine screw 74 and washer 72, disengaging the cam block from dowels 80, and then turning cam block 68 through 180°, the surface shown lowermost in Figure 4 can be placed uppermost to engage the cam 90. Because the blocks 68 and 70 include large surface areas, unit loads are decreased. Hence, wear is reduced and minimized.

Referring to the lubrication arrangement disclosed in Figures 1, 7 and 8, it will be observed that this arrangement comprises the provision of an aperture 110 on the inner portion of the bearing sleeve 60, i. e., the portion nearest the table axis. Aperture 110 is positioned just below the lower end of the depending sleeve 48 of filling table 34. As is indicated in Figure 8, aperture 110 is of sufficient extent circumferentially of the bearing 60 that lubricant jetted from two diverging nozzles diagrammatically shown by the arrows 112 (and one of which nozzles is shown in each of Figures 1 and 7) moves through the aperture 110 and upon the outer wall of the cylinder 56. The fixed bearing sleeve 60 is provided with a groove 114 which extends entirely about its inner surface, groove 114 being downwardly inclined to a point diametrically opposite aperture 110. As a result, oil jetted through aperture 110 from the nozzles 112 moves downwardly and around the groove 114 to apply lubricant to the outer surface of the reciprocable cylinder 56. The lubricant jetting nozzles 112 may be periodically and manually operated by an attendant.

Figures 9 to 17 best illustrate the arrangements included in the present invention for journaling the filling table 34 upon the pedestal 32 of base 30, or to journal a crowning or syruping table. The journaling arrangement of the present invention may be generally described as involving the following: A neoprene or other resilient gasket 120 preferably closely fits a recess in a bearing holder 122 as shown in Figures 9 and 10, but which may fit in a recess 123 of the pedestal itself as shown in Figure 1. In any event, a ring 124 preferably formed of hardened stainless steel rests upon the gasket 120 and is doweled through the gasket to the pedestal or the bearing holder 122 by dowel pins such as indicated in Figure 9. A second ring 126, preferably formed of phosphor bronze, is doweled to the lower and flat surface 128 of the filling table skirt 44 and rotates upon the lower and fixed ring 124.

The form of the bearing holder 122 is best shown in Figures 15 to 17, from which figures it will be observed that the bearing holder includes

a recessed annular surface concentric with the pedestal and which surface is designated 130. These figures also indicate how the bearing holder 122 may be doweled to the pedestal as by pins 132 and also may be provided with lubricant supply passages 134 and 136 as shown in Figure 10, as well as drain passages. It will be noted that the lubricant passages respectively open to the surface 130 or through the inner surface of wall 138 above surface 130. The outer and inner edges of recess 130 are respectively defined by the walls 138 and 139.

The gasket 120, formed of neoprene or other resilient material, closely fits within the recess which forms surface 130 and may be of the order of $\frac{3}{16}$ " in thickness. When used in a filling table bearing, ring 120 will have a transverse width of the order of 1.75 inches and an overall diameter of the order of 10.5 inches. The rings 124 and 126 will be of similar widths and overall diameter when used with a filling table. All of the rings will be of smaller transverse width and overall diameter when used to support a syruping or crowning table. The neoprene or other resilient ring 120 will have an elasticity rating of the order of 80 to 85 when used with a filling table.

As is best shown in Figure 17, the resilient ring 120 will be held against turning movement by dowel pins such as indicated at 146 which extend upwardly through the resilient ring from the bearing holder 122 and thence into the lower portion of the lower metal bearing ring 124.

The lower bearing ring 124 is best illustrated in Figures 13 and 14 and is shown in various sections in Figures 9 and 10. As is indicated in these views, the upper or bearing surface of ring 124 has a groove 142 therein, which groove is arranged eccentrically of the ring and has a cross-sectional width of the order of $\frac{1}{16}$ " and a depth of approximately half the depth of the ring, which latter depth will approximate one-half an inch. Groove 142 is of such diameter and so positioned that at one point in its circumference, it will be closely adjacent the inner edge of ring 124, while the diametrically opposite portion of the groove will be closely adjacent the outer edge of the ring. As best shown in Figures 10 and 14, an aperture 144 extends from the lower surface of ring 124 to the groove 142. The ring will be secured to the pedestal or bearing holder with aperture 144 in vertical alignment with the lubricant supply passage 134 of bearing holder 122. Because the resilient gasket 120 is also apertured at this point, lubricant may be flowed upwardly through the passage 134 to the groove 142.

The upper bearing ring 126 is somewhat thicker in axial section than ring 124. In addition, as is best shown in Figures 11 and 12, the lower and bearing surface of upper ring 126 is provided with a plurality of grooves 148, preferably three in number, which extend from the inner circumference or edge of the ring to its outer circumference. The grooves 148 are equidistantly spaced about the ring 126 and extend along lines parallel to tangential lines which contact the ring at equidistant points. Ring 126 is provided with apertures 150 into which dowel pins 152 extend as shown in Figure 9 to cause the ring to rotate with the filling table. As is best shown in Figure 10, the passage 136 of the bearing holder 122 opens through the wall 138 of the bearing holder recess at a point opposite the bearing surfaces of the rings 126 and 124 so that oil moving up through the passage 136 will enter the outer ends of the

grooves 148 as they move opposite the mouth of the passage.

As the filling table is rotated by the usual driving system, not shown, the movement of the grooves 148 of upper ring 126 with respect to the circular and eccentrically arranged groove 142 of lower ring 124 will cause oil or other lubricant to be swept across the entire bearing surface.

A filling table may have a diameter of from three to ten feet and as the table rotates, a downward thrust is directed upon successive points of its periphery adjacent the stationary table of the filling machines, this downward thrust being occasioned by the downward pulling movement exerted upon the bottle supporting platforms by the cam 99. Therefore, a filling table must be mounted in bearings which will resist this thrust and thereby prevent the table from having a tilting or rocking motion. It has been found that the provision of flat bearing rings such as those described above, with the lower ring mounted upon a resilient gasket supported in a completely and closely confined space such as the recessed surface 130 fully supplies the necessary bearing surface. Also, the resilient gasket permits the lower plate to remain in alignment with the upper plate, thereby distributing the load over all or most of the bearing surface.

As is described in the above-mentioned Huntley and Stewart patent, No. 2,145,765, and Stewart and Rever patent, No. 2,353,523, it is usual to have the counter-pressure trip of a beverage filling machine so arranged that when a container supporting platform without a container thereon moves adjacent the trip, the trip will be withdrawn from the path of movement of the filling valve arm. Figures 18 to 20 of the present drawings disclose an improved arrangement for this purpose. Figure 18 diagrammatically shows the filling trip generally designated 160 mounted within a housing 161 carried upon a bracket 162 suitably secured to the stationary table of the machine in the manner described in the above-mentioned patents. The plunger 164 comprising the actual trip will be positioned in such a horizontal plane that with the filling table rotating in the direction of the arrow of Figure 20, and a valve arm 166 of a filling head 168 in closed or non-flow position, trip 164 will strike lug 167 of the valve arm 166 and turn the latter to the dotted line position 166a of Figure 18, viz., counterpressure position. When the arm is in position 166a, it will next be struck by the filling trip 170 so as to be moved to filling position. Obviously, if the counterpressure trip plunger 164 is withdrawn from the outward position shown in Figure 20 to the inward position shown in Figures 18 and 19, the lug 167 of valve arm 166 will then move beneath the filling trip 170 so that the valve will be left in closed position.

As is described in the above-mentioned Stewart and Rever patent, the counterpressure trip device includes an electromagnet or solenoid 172 which is normally deenergized. However, when a container supporting platform 50 moves upwardly to the solid line position of Figure 18 because no bottle has been placed thereon to engage the filling head and thereby limit upward travel of the platform, the outer edge of the platform will brush against the upper end of the lever 174 so that a switch 176 will be closed to energize the solenoid 172. Energization of the solenoid 172 will cause the armature 178 to be drawn inwardly or to the left in Figures 18 and 19 to move the plunger 164 to the position shown in those figures.

Plunger 164 is normally urged outwardly or to the right in Figures 18 and 19 by a spring 196 having its inner end bearing against the plunger housing 161 and its outer end bearing upon a collar 182 fixed to the plunger. Plunger 164 includes a bore 184 having a collar 186 threaded in its rearward end. The outer end of armature 172 has a swivel connection through a pin 188 to a bracket 190. Bracket 190 is apertured to receive the outer end of a pin 192, the outer end of the pin having a washer 194 secured thereto which contacts with the inner surface of bracket 190. Pin 192 extends into the bore 184 of plunger 164 and a head 194 is provided at the outer end of the pin. A spring 196 has its outer end bearing upon the inner surface of head 194 while its opposite end bears upon the inner surface of the collar 186. The spring 196 thereby serves as a driving connection between the armature 178 and the plunger 164.

By the plunger structure described above, when solenoid 172 is energized, armature 178 will be drawn to the left, imparting a corresponding movement to the pin 192 through the swivel connection 188. Under normal conditions, spring 196 will then act upon the collar 186 to draw the plunger 164 inwardly. However, should the plunger 164 be seized in housing 161 for some reason, so that it cannot be moved inwardly, spring 196 will be compressed. The provision of the spring 196 thereby prevents the solenoid 172 from being damaged by electrical overload in the event the plunger is seized and cannot move inwardly. The provision of the swivel connection 188 between armature 178 and plunger 164 minimizes the possibility of the plunger becoming seized in housing 161. In other words, the plunger cannot become seized because of any lack of axial alignment thereof with the path of movement of the armature.

Figures 21 to 23 disclose a filling head 168 of the present invention. The filling head illustrated is of the general type disclosed in the above-mentioned Stewart Patent No. 2,367,899 in that it includes a valve body 200 having its inward or rearward face 202 held against a fitting 204 secured to the periphery of the upper and reservoir carrying portion of the filling table.

As is indicated in Figure 23, the valve body 200 is provided with a gas passage 206 and a liquid passage 208 respectively connected to tubes (not shown) leading to the upper and lower portions, respectively, of the filling reservoir. These passages open to ports, not shown, in the seat face 210 of the valve body 200. The filling nozzle 212 depending from the filling head is provided with water and gas passages similar to those of the last-mentioned Stewart patent and which passages also open to the seat face 210 of the valve body. A disc valve element 214 is rotatable upon the valve body seat face 210 to control counter-pressure flow, and filling and return flow to the reservoir. Valve 214 is rotatable about a sleeve 216 as indicated in Figure 21, the inner portion of sleeve 216 being threadedly fixed in a bore 217 which extends centrally through the valve body 200.

Sleeve 216 supports a poppet type snift valve including an actuating plunger portion 218, a shank portion 220 and a valve portion 222. The plunger portion 218 includes a head 224 which is slidable through an apertured cap 226 threaded in the outer end of the stem 216. Inwardly of cap 226, plunger portion 218 is threaded to receive collars 228 and 230. Collar 228 is adapted to contact with the inner surface of cap 226

to limit the outward movement of plunger portion 218 while collar 230 is adjustable to vary the contact of the plunger with the stem portion 220 of the snift valve. The outer end of the stem portion 220 is recessed so that a flange on collar 230 may move into the same. Upon inward movement of plunger portion 218, the shoulder 232 of collar 230 will contact with the flange of the recessed portion of stem 220. The remainder of stem 220 is of reduced diameter and is surrounded by a coil spring 234, the inner end of the coil spring bearing upon a shoulder provided in the sleeve 216. A groove 236 of substantial width axially of the stem surrounds the stem adjacent its inner end. Upon the reduced portion thus provided, the stem is fitted with the valve element 222 including a resilient gasket 238 which normally seats on the inner end of sleeve 216 as shown in Figure 21. It will be noted from Figure 21 that the valve element 222 is movable in a chamber 240 formed by the innermost portion of bore 217. Spring 234 serves to hold the valve in the position illustrated in Figure 21.

A passage 242 communicates with the filling nozzle 212 in the manner described in the above-mentioned Stewart Patent No. 2,367,899 so that gases trapped in the upper portion of the bottle may flow through passage 242 to the chamber 240. When trip 218 is moved inwardly by brushing contact with a snift striker 244 as indicated in Figure 21, valve 222 will be moved to the position shown in Figure 22. At that time, the trapped gas may move along the reduced stem portion 236 of the valve and thence through radial passages 246 (Figure 22) joined by a circumferential groove 248 in sleeve 216. A passage 250 provided in the valve body 200 has its inner end opposite the grooved portion 248 of sleeve 216. As a result, gas moving through the grooved portion 248 will enter passage 250. A snift fitting 252 will be secured in the outer portion of passage 250. As is indicated in Figure 21, passage 250 is so inclined in body 200 so that it extends rearwardly of the body. As is shown in Figure 23, passage 250 also is inclined laterally. By the first-mentioned arrangement, the fitting 252 will be directed inwardly of the filling table, viz., toward the filling table axis, while by the last-mentioned arrangement the fitting will be laterally disposed with respect to the filling nozzle.

The feature of having the snift fitting 252 directed toward the axis of the filling table prevents snifted gases and liquid from blowing toward an attendant. Also, any liquid and gases which may be snifted will be directed toward the base of the machine, rather than upon the floor of the bottling plant.

The terminology used in the specification is for the purpose of description and not of limitation, the scope of the invention being defined in the claims.

We claim:

1. In a filling machine, a base, a table rotatable on the base about a vertical axis, a container supporting platform carried by and vertically reciprocable with respect to the table, vertical guideways fixed to the table, means to urge the platform in one vertical direction, a cam fixed to the base and positioned adjacent the path of rotary travel of the platform with the table, said cam including a horizontal face and faces inclined to the horizontal; and means carried by the platform and cooperating with the cam to move the platform in the opposite vertical di-

reaction and comprising a block element having its periphery provided with a series of planar surfaces respectively lying in planes corresponding to those in which the cam faces lie.

2. A filling machine of the character described in claim 1 wherein each block element is provided with two series of said surfaces, each surface of one series lying at an angle of 180° to the corresponding surface of the other series.

3. In a filling machine, a base, a table rotatable on said base about a vertical axis, a container supporting platform carried by and vertically reciprocable with respect to the table, a guideway fixed to the table including two opposed and vertically extending surfaces, and an element rotatably carried by the platform between said surfaces and including a pair of vertically extending faces respectively adapted to engage the surfaces of the guideway, said element being provided with a second pair of similar faces lying at an angle to the first-mentioned pair of faces and adapted to be brought into engagement with said guideway surfaces upon rotation of said element with respect to the platform.

4. In a filling machine, a base, a table rotatable on said base about a vertical axis, a container supporting platform carried by and vertically reciprocable with respect to the table, guide means fixed to the table including spaced and opposed vertical surfaces, a pin projecting laterally from the platform between said surfaces, means to urge the platform in one vertical direction, a pair of block elements positioned on the platform pin, one of the block elements lying directly between the opposed surfaces of said guide means and the other lying in a second plane, and a cam fixed to the base and positioned in the path of travel of the last-mentioned block element, said cam including a horizontal face and faces inclined to the horizontal, each of said block elements including planar faces.

5. In a filling machine, a base, a pedestal on said base and including an annular and upwardly facing area, a table rotatable on said pedestal, vertically reciprocable container engaging elements mounted on said table, means fixed with respect to said base positioned at one point in the path of rotation of said table to move said elements vertically and thereby exert a vertical thrust upon said table including an annular and downwardly facing area, a pair of bearing rings respectively including horizontal and planar surfaces in opposed engagement, the rings being respectively secured to the areas of the pedestal and the table, and a resilient gasket confined within the annular and upwardly facing area of the pedestal to support the bearing ring.

6. A filling machine of the character described in claim 5 wherein the bearing face of one of the rings is provided with a circumferential groove positioned eccentrically of the ring.

7. A filling machine of the character described in claim 5 wherein the bearing face of one of the rings is provided with a groove extending between the inner and outer peripheries of the ring, the inner and outer ends of the groove lying on a line substantially parallel to a line tangential of the ring.

8. In a filling machine, a base, a table rotatable on the base about a vertical axis, filling heads and vertically reciprocable container supporting platforms carried at the periphery of the filling table, the filling heads including valves rotatable about an axis radial of the table and valve operating arms projecting radially of the

axis of each valve, valve trip means carried by the base adjacent the periphery of the filling table, said trip means including a plunger positioned in the path of movement of the valve operating arms with the table, means to move the plunger into the path of travel of the valve arms, a second means to move the plunger in the opposite direction, means to actuate the last-named means operable when no container is present

5 upon a platform, and a resilient element operatively connecting the plunger and said second plunger operating means.

10 9. A filling machine of the character described in claim 8 wherein said second plunger operating means comprises a solenoid.

15 10. A filling machine of the character described in claim 8 including a swivel connection between the plunger and said second operating means.

11. The combination in a filling machine having a reservoir for liquid and gas and rotatable about a vertical axis, of a filling head adjacent the reservoir periphery and including a valve body, the valve body having a horizontal bore therein opening to its seat face, the valve body

20 25 having a series of passages therein for liquid and gas communicating with a reservoir and leading to the seat face of the valve body, a sleeve fixed in the valve body bore and projecting outwardly from said face, a filling nozzle on the filling head and adapted to be positioned in a container, the valve body having a second series of passages therein leading from the seat face of the valve body to the filling nozzle, a valve rotatably mounted upon said sleeve to engage said face

30 35 of the valve body and having passages therein adapted, upon seriatim movements of the valve, to bridge corresponding passages of the two series of passages in the valve body to permit gas to flow from the reservoir to the container, and to

40 45 provide liquid flow from the reservoir to the container and simultaneously vent the container to the reservoir, the valve body including a first snift passage extending from the filling nozzle to said bore and a second snift passage extending from said sleeve to the exterior of the valve body and atmosphere, and a poppet valve including a stem movable in said sleeve to place the two last-mentioned passages in communication, the seat surface of said poppet valve being engageable with the inner end of said sleeve.

50 55 12. The combination defined in claim 11 wherein the snift passage opens to atmosphere in a direction facing the axis of rotation of the reservoir.

13. The combination defined in claim 11 wherein in the poppet valve stem is axially recessed and the sleeve is radially ported to provide a flow passage between the inner end of the sleeve and the valve body snift passage.
